UNITED STATES PATENT OFFICE.

JOSEPH FOSSA, OF NEW YORK, N. Y., ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,315,486.

Specification of Letters Patent. Patented Sept. 9, 1919.

Application filed August 13, 1917. Serial No. 185,905.

To all whom it may concern:

Be it known that I, JOSEPH FOSSA, a citizen of the United States, residing at New York, in the county of New York and State 5 of New York, have invented certain new and useful Improvements in Sewing-Machines; and I do hereby declare the following to be a full, clear, and exact description of the invention, such as will enable others 10 skilled in the art to which it appertains to make and use the same.

The invention relates to thread severing and holding mechanism for sewing machines.

15 The object of the invention is to provide a novel and improved mechanism which is well adapted for severing the upper needle thread of a buttonhole making machine at the completion of a buttonhole, and for 20 holding the severed end preparatory to the sewing of a succeeding buttonhole, and which may be arranged to sever the thread close to the work and also to hold the free end at the beginning of the seam close to the work 25 and in position to be covered by the over-seam, so that both waste ends of thread are comparatively short, and the end at the beginning of the seam may be uniformly and completely covered thereby.

30 To these ends the invention comprises the features of construction and combinations of parts hereinafter described and referred to in the claims, the advantages of which will be apparent to those skilled in the art 35 from the following detailed description of the mechanism illustrated in the drawings, which embodies the invention in its preferred form.

In the drawings Figure 1 is a sectional 40 elevation showing so much of a buttonhole sewing machine as is necessary to illustrate the application of the present invention thereto; Fig. 2 is a sectional plan view showing the mechanism for operating the thread 45 holding and cutting devices; Fig. 3 is a detail side elevation of the thread holding and cutting devices, one plate of the supporting bracket being removed to show the parts which are mounted in the guideway within 50 the support; Fig. 4 is a detail view of the plate which is removed from Fig. 3; Fig. 5 is a sectional view on line 5 of Figs. 3 and 4; Fig. 6 is a sectional view on line 6 of

Figs. 3 and 4; Fig. 7 is a view showing the carrier slide for the thread finger and the 55 thread holding and cutting plates detached; and Figs. 8 to 17 inclusive are a series of views illustrating the mode of operation of the thread holding and cutting devices.

In the drawings the invention is shown as 60 embodied in a buttonhole sewing machine having the construction and mode of operation of the machine shown and described in Patent No. 1,063,880, dated June 3, 1913. In this machine the stitch forming mechanism 65 comprises an upper needle 2 eccentrically mounted in a vertically reciprocating needle bar 4, an under needle 6, and a looper 8. The upper needle bar is mounted in a rotary head or carrier 10. The under 70 needle and looper are mounted in a rotary turret 12 which is rotated in unison with the head 10. The work is held by clamps 14 pivotally mounted on the work supporting plates 16, which are in turn mounted on a clamp carrier 18. The clamp carrier is moved lengthwise of the buttonhole to bring the work into register with the cutter or 75 with the sewing mechanism and to feed the work during the sewing by a cam groove 80 formed in the cam gear 20 which makes one revolution for each cycle of the machine. The clamp carrier is moved laterally and 85 the stitch forming mechanism is rotated during the sewing through suitable connections from a gear 22 which makes one revolution during the sewing of a buttonhole. The cutter 24 is operated from a cam on the cam gear, and when operated to cut a buttonhole, also acts to close the clamps. 90 The clamps are held closed during the sewing by latching devices, and are released during the return of the cutter carriage to cutting position, as fully described in the patent above referred to. At the completion 95 of the sewing of a buttonhole the stitch forming mechanism is stopped with the upper and under needles in their retracted positions, and with the upper needle thread about the looper, as indicated in Fig. 1.

100 The means for severing and holding the thread at the completion of the sewing comprises a thread engaging finger which is mounted to swing transversely of the standing needle thread so that the thread is deflected into position to be acted on by clamp-

ing and cutting plates which pass on opposite sides of the finger and cooperate therewith to clamp and sever the thread. To adapt the holder to present and maintain the held end of the thread in line with the stitches being sewn at the beginning of the seam, the holder is mounted to move laterally of the seam as the sewing mechanism is rotated at the beginning of the sewing, thus 10 maintaining the thread in alinement with the seam while the end is being covered thereby. This movement is preferably secured by mounting the thread holder and cutter on the rotary needle carrier so that it remains in fixed relation to the sewing mechanism during the rotation of this mechanism.

In the construction shown the thread engaging finger 26 projects laterally from an arm 28 mounted to swing about a horizontal pivot 30 on the lower end of a vertically movable carrier slide 32. The carrier slide is mounted in a substantially vertical guideway formed in a supporting bracket 34 which is secured to a plate 36 on the lower end of the rotary needle carrier 10. The carrier slide is held in the guideway in the bracket by a cover plate 38 secured to the side of the bracket. The thread clamping plate 40 and the thread cutter plate 42 are mounted within the guideway on opposite sides of the carrier slide 32 and parallel to the pivot 30 so that they may pass on opposite sides of the thread arm 28 and of the thread engaging finger 26. 30 These two plates are connected to move in unison by an arm 44 which projects from the cutter plate through a slot 46 in the upper end of the carrier slide 32, and fits within a slot 48 in the upper end of the thread clamping plate 40. An arm 50 projects from the opposite side of the plate 42 through a slot in the supporting bracket 34 and into position to be engaged by the forward end of an operating lever 52 when the sewing mechanism is in its stopped position. A similar arm 54 projects from the carrier slide 32 through the slot in the supporting bracket and into position to be engaged by an operating lever 56 which also underlies the arm 50. The carrier slide and the plates are forced downward by spring-pressed pins 58 and 60 which are mounted within recesses in the plate 38 and engage arms 62 and 64 which project into the recesses from the carrier slide and cutter plate. The downward movement of the carrier slide and cutter and clamping plates is determined by the engagement of the arms with the lower ends of the recesses. The inner end of the thread arm 28 is engaged by a leaf spring 66 which tends to swing the arm laterally about its pivot and to carry the thread finger to the opposite side of the needle path, as indicated in Figs. 1, 3, 8 and 9. When the cutter and clamping plates are in their lower

position they hold the thread arm in substantial alinement with the carrier slide against the pressure of the spring 66.

During the sewing of the buttonhole, the carrier slide and the thread cutter and thread clamp plates are in their lower positions at one side of the needle path. After the sewing is completed the lever 52 is operated to raise the cutting and clamping plates into the position indicated in Fig. 3, so that the 70 thread arm 28 is swung laterally to bring the thread finger on the opposite side of the needle path. As the work clamp is retracted toward cutting position the thread is carried toward the thread arm and into position to be engaged by the thread finger, as indicated in Fig. 10. The lever 52 then releases the cutting and clamping slides, which are forced quickly downward to their lower position by the spring-pressed pin 60. During the first part of this movement the plates act on the thread arm 28 to swing it laterally about its pivot, as indicated in Fig. 11. This movement of the thread arm carries the thread finger against the standing thread 80 and obliquely downward toward the work, so that the thread is bent or looped about the thread finger which, when in its lower position, is close to the upper surface of the work. The final downward movement of the 90 thread clamping and cutting plates carries the clamping plate along the front face of the thread finger, thus clamping the thread, and carries the lower edge of the cutter plate over the rear surface of the thread finger, 95 thus severing the thread, as indicated in Fig. 12. As the work clamps are opened the operating lever 56 acts to raise both the carrier slide 32 and the thread clamping and cutting plates into the position indicated in Fig. 13, 100 so that they will not interfere with the opening movement of the work clamps. When the machine is started in making the succeeding buttonhole, the operating lever 56 allows the carrier slide and the plates to move 110 downward into their lower position, as indicated in Fig. 14, so that they hold the thread end close to the work during the sewing of the initial stitches. The upper needle enters the work in line with the buttonhole in forming the initial stitch, as indicated in Fig. 16, and during the sewing of the first few stitches of the seam the sewing mechanism is rotated through a quarter of a revolution. The support for the thread 115 holder is arranged to hold the thread end in position to be covered by the initial stitches of the seam and substantially in alinement with the seam, as indicated in this figure. During the rotation of the sewing mechanism through a quarter revolution the thread holder is swung laterally and toward the buttonhole slit, so that the thread is maintained in alinement with the seam as the seam progresses, and until the thread end 120 125 130

is withdrawn from the holder, as indicated in Fig. 17. This insures the complete covering of the free end of the thread by the stitches of the overseam.

- 5 The operating levers 52 and 56 are forced in a direction to lower the carrier slide and thread cutting and clamping plates by springs 68 and 70 indicated in Figs. 1 and 2. The levers are rocked at the proper intervals by cams 72 and 74 secured to the cam gear 20, as indicated in Figs. 1 and 2. The cam 72 engages an arm 76 secured to a rock shaft 78, the outer end of which carries an arm 80 which is connected to the rear 10 end of the lever 52 by a pin and slot connection 82. The cam 74 engages one arm of a lever 84 which is mounted to turn on the rock shaft 78, and the other end of which is connected by a pin and slot connection 86 15 with the rear end of the lever 56.

While it is preferred to employ the specific construction and arrangement of parts shown and described, especially in embodying the invention in a machine of the patent 25 above referred to, it will be understood that this construction and arrangement is not essential to the broader features of the invention, but may be varied or modified as found desirable or best suited to the construction and mode of operation of the machine in which the invention is to be incorporated.

Having explained the nature and object 30 of the invention, and specifically described one form of machine in which it may be embodied, what is claimed is:—

1. A sewing machine, having, in combination, a rotary stitch forming mechanism, thread severing and holding devices 40 mounted to move with the stitch forming mechanism in its rotary movement, and mechanism for actuating the devices to sever and hold the thread at the completion of the sewing.
- 45 2. A sewing machine, having, in combination, an upper needle and means coöperating therewith to form overseam stitches, a rotary carrier for the upper needle, and devices for severing and holding the needle 50 thread above the work mounted to rotate with the carrier.

55 3. A sewing machine, having, in combination, an upper needle and means coöperating therewith to form overseam stitches, a rotary carrier for the upper needle, and means moving with the carrier in its rotary movement for holding the end of the needle thread in line with the seam until covered thereby.

- 60 4. A sewing machine, having, in combination, an upper needle and means coöperating therewith to form overseam stitches, a rotary carrier for the upper needle, mechanism for rotating the upper needle carrier 65 timed to turn it during the sewing of the

initial stitches, a thread holder for holding the end of the needle thread at the beginning of the sewing, and means for moving the holder transversely of the seam during the turning of the needle carrier to maintain the thread in alinement therewith.

5. A sewing machine, having, in combination, stitch forming mechanism comprising a vertically reciprocating needle, a thread engaging finger mounted to swing about a 75 horizontal axis and to deflect the standing needle thread at the completion of the sewing, and reciprocating thread clamping and cutting members coöperating with the opposite sides of the finger.

6. A sewing machine, having, in combination, stitch forming mechanism comprising a vertically reciprocating needle, a thread engaging finger mounted to move in an inclined direction toward the work in deflecting the standing needle thread, and thread clamping and cutting members coöperating with the finger in its lower position.

7. A sewing machine, having, in combination, stitch forming mechanism comprising 90 a vertically reciprocating needle, a thread finger mounted to reciprocate transversely of the standing needle thread, and vertically reciprocating thread clamping and cutting plates mounted to pass on opposite sides 95 of the finger.

8. A sewing machine, having, in combination, stitch forming mechanism comprising a vertically reciprocating carrier, a thread finger pivoted to the lower end of the carrier, and thread clamping and cutting plates mounted to reciprocate on opposite sides of the carrier and finger.

9. A sewing machine, having, in combination, a work clamp, stitch forming mechanism comprising an upper needle and a complementary under thread mechanism, rotary supports for the stitch forming mechanism, thread cutting and holding devices mounted to rotate with said supports, and mechanism 100 for operating the devices to sever and hold the needle thread above the work at the completion of the sewing.

10. A sewing machine, having, in combination, a work clamp, stitch forming 115 mechanism comprising an upper needle and a complementary under thread mechanism, rotary supports for the stitch forming mechanism, thread cutting and holding devices mounted to rotate with said supports, 120 and mechanism for operating the devices to sever and hold the needle thread above the work at the completion of the sewing and for moving them away from and toward the work.

11. A sewing machine, having, in combination, stitch forming mechanism comprising a vertically reciprocating needle, a rotary carrier therefor, a substantially vertical support secured to the carrier at one 130

side of the needle path, a vertically movable carrier slide in the support, a thread finger pivoted to the lower end of the slide to swing laterally to the opposite side of the needle path, and thread clamping and cutting plates arranged to reciprocate on opposite sides of the carrier slide and thread finger.

12. A sewing machine, having, in com-

bination, rotary stitch forming mechanism, 10 thread severing and holding devices mounted to rotate with the stitch forming mechanism, and mechanism for moving the devices toward the needle path, operating them to sever and grip the thread, and then 15 returning them to their initial position.

JOSEPH FOSSA.
